CONTAINER

Morris Weisenberg, Los Angeles, Calif.

Application May 18, 1942, Serial No. 443,500

1 Claim. (Cl. 221—79)

The present invention relates to new and useful improvements in containers, particularly for cold cream, tooth paste, shaving cream, etc., and has for its primary object to provide, in a manner as hereinafter set forth, a device of this character comprising novel means whereby the contents may be conveniently dispensed as desired in a neat, sanitary manner.

Other objects of the invention are to provide a dispensing container of the aforementioned character which will be comparatively simple in construction, strong, durable, highly efficient and reliable in use, compact, attractive in appearance, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a dispensing container constructed in accordance with the present invention.

Figure 2 is a view in vertical section through the device.

Figure 3 is a view in horizontal section, taken substantially on the line 3—3 of Figure 1.

Figure 4 is a view in vertical section through the upper portion of the device with the cap omitted, showing the follower operating shaft in section.

Figure 5 is a fragmentary view in horizontal section, taken substantially on the line 5—5 of Figure 2.

Figure 6 is a view in side elevation of the follower actuating shaft showing the operating knob in section.

Figure 7 is a top plan view of the follower.

Figure 8 is a detail view in vertical section through the removable cap.

Referring now to the drawings in detail, it will be seen that the embodiment of the invention, which has been illustrated, comprises a substantially cylindrical receptacle 1 of suitable material for the reception of the paste or cream. The receptacle 1 may be of any desired dimensions. The receptacle 1 comprises, on its upper end, a substantially conical shoulder 2 from which an externally threaded discharge neck 3 rises. A cap 4 is threaded on the neck 3. The bore 5 of the neck 3 includes the counterbored inner or lower end portion 6, the purpose of which will be presently set forth. As best seen in Figure 2 of

the drawings, the cylindrical receptacle 1 is internally threaded, as at 7.

A closure cap 8 is threadedly mounted on the lower end portion of the receptacle 1. The closure 8 includes a centrally located, upwardly protruding bearing 9. A shaft 10, which extends centrally through the cylindrical receptacle 1, has one end portion journaled in the bearing 9. The counterbore 6 of the bore 5 constitutes a bearing for the other end portion of the shaft 10. The substantially cup-shaped operating knob 11 is formed integrally with the lower end of the shaft 10, said knob rotatably fitting on the closure 8. Adjacent the upper end of the bearing 9, the shaft 10 has formed therein a circumferential groove 12. The groove 12 accommodates a split ring 13 which secures the shaft 10 in the closure 8.

The shaft 10 is further provided with a pair of longitudinal channels 14. The channels 14 extend from a point adjacent the groove 12 to the upper end of the shaft 10 and terminate in tapered or enlarged upper end portions 15 (see Fig. 4).

A substantially conical follower 16 is threadedly mounted in the receptacle 1 and slidable on the shaft 10. The follower 16 includes an annular, centrally located bearing 17 having diametrically opposite ribs 18 therein which are engaged in the channels 14. Thus, the follower 16 is connected to the shaft 10 for rotation therewith.

It is thought that the operation of the device will be readily apparent from a consideration of the foregoing. Briefly, the cap 4 is removed and the knob 11 is turned for rotating the shaft 10. Rotation of the shaft 10 threads the follower 16 toward the discharge end of the receptacle 1 for ejecting the contents of said receptacle. The paste or cream flows through the channels 14 into the bore 5 of the neck 3. The tapered or enlarged end portions 15 of the channels 14 assure the free passage of the contents into the bore 5. In addition to connecting the follower 16 to the shaft 10, the ribs 18 clear the channels 14 as said follower moves toward the discharge end of the receptacle. The conical follower 16 conforms substantially to the correspondingly shaped shoulder portion 2 of the receptacle 1 and is adapted to enter said portion. Thus, practically all of the contents of the tube may be forced therefrom. The complete dispensing assembly, comprising the members 10, 11, 16, etc., may be expeditiously removed from the receptacle 1 by simply unscrewing the closure 8.

It is believed that the many advantages of a container constructed in accordance with the

present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

A container comprising an internally threaded cylindrical receptacle, a closure on one end of the receptacle, a discharge neck on the other end

of said receptacle, a bearing in the inner portion of the neck, a shaft journaled in the closure and the bearing, this shaft having longitudinal grooves therein, a follower threadedly mounted in the receptacle and encircling the shaft, and ribs on the follower engaged in the grooves for connecting said follower to the shaft for rotation therewith, the grooves communicating with the discharge neck for conveying material from the receptacle thereto.

MORRIS WEISENBERG.
